CLAIM

The ornamental design for a digital display soldering iron, as shown and described.

DESCRIPTION

FIG. 1 is a front and top perspective view of a digital display soldering iron, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion of the digital display soldering iron indicated in circle 9 in FIG. 1; and,

FIG. 10 is an enlarged view of a portion of the digital display soldering iron indicated in circle 10 in FIG. 7.

The broken lines in the figures illustrate portions of the digital display soldering iron that form no part of the claimed design. The dot-dash broken lines in the figures depict the boundaries of the claimed design and form no part thereof.
